UNITED STATES PATENT OFFICE.

CHARLES LAURENCE BURDICK, OF WOOD GREEN, ENGLAND, AND HENRY PERVILHAC, OF VILLEURBANNE, FRANCE.

PROCESS OF STENCILING.

SPECIFICATION forming part of Letters Patent No. 757,438, dated April 19, 1904.

Application filed September 10, 1903. Serial No. 172,671. (No specimens.)

To all whom it may concern:

Be it known that we, CHARLES LAURENCE BURDICK, artist, a citizen of the United States, residing at No. 4 Eastern road, Wood Green, in the county of Middlesex, England, and HENRY PERVILHAC, manufacturer, a citizen of the French Republic, residing at No. 15 Chemin de la Doua, Villeurbanne, in the Department of Rhône, France, have invented new and useful Improvements in Processes of Stenciling, of which the following is a specification.

This invention relates to a process for coloring, decorating, or printing textile and other fabrics.

Hitherto, apart from dyeing and stenciling, the decoration of fabrics, paper, and other similar materials has been effected either by printing-rolls or by blocks, and where patterns were desired having more than one color it has been usual to print, by means of blocks or rollers, a stopping-out material or medium according to pattern over such parts of the fabric as is desired should be left plain or which have been previously decorated or which are to be decorated with another color.

Stencil-work as heretofore done has been a simple process of coloring by projecting or spraying color through the apertures in the stencil, and that method limits the possible designs to such patterns as can be pierced or cut in the form of openings in the stencil, for it has been heretofore impossible to produce a stencil with a design not joined or connected in some manner with the main portion of the stencil-plate (which imposes restrictions as to the work, thus limiting the designs to a narrow field) unless wires or wire-gauze were employed, and the isolated design or designs were then suspended by wires or laid on the wire-gauze and fixed thereto; but this interferes with the quality of the work produced.

Figure 1 of the drawings represents a class of design which it was not possible to produce hitherto except by using wire-gauze or the like. Fig. 2 shows the kind of stencil which was used to produce as nearly as might be such a design. Fig. 3 shows part of a stencil adapted to stop out part of a similar design when made according to this process. Fig.

4 illustrates the stencil for use when putting on the color over the stopping-out medium applied previously, and Fig. 5 represents the pattern on the material before the stopping-out material has been removed.

Assume, for example, it is desired to produce a pattern such as is shown in Fig. 1, which particular pattern is only shown as an example because of its simplicity. Usually in trying to produce a pattern of this kind the stencil-maker produces a stencil as shown in Fig. 2, of which the middle part *a* is connected to the body part *b* of the stencil by connecting parts *c c*. That, however, does not produce the pattern desired. Now according to this invention a stencil, and preferably an endless revolving stencil, is employed, and stopping-out material or medium is thrown onto the fabric or other material to be decorated, so as to cover a number of small circles or other designs, as shown in Fig. 3, by means of brushes or spraying apparatus or otherwise, such spraying apparatus being of the kind used to project color in the form of a fine spray onto paper, fabrics, or other objects, while the stencil is perforated with the designs or patterns which it is desired to stop out. When the fabric or other material is covered as far as is desired with the stopping-out medium and the latter has been dried, if necessary, the fabric is decorated or printed by means, for example, of spraying apparatus by employing a stencil, as shown, for instance, in Fig. 4, with larger or differently-shaped apertures, and when the decoration or coloring or that stage thereof has been completed, as shown in Fig. 5, the stopping-out medium is removed by soaking or washing in some kind of fluid or liquid—such as benzene, for example—which has the effect of removing the said stopping-out medium and leaving the pattern, as shown, for example, in Fig. 1, as was originally intended. The stopping-out medium may be variously composed, and a suitable medium consists of resin, paraffin, beeswax, and turpentine, which form a sort of cement or mastic, which latter does not permit the color to penetrate to the material or fabric, but is easily removable when

the material has been subsequently colored by washing with or dipping the same into a bath of benzene, as aforesaid. The stopping-out medium is then quickly dissolved, leaving 5 the stopped-out pattern on the fabric or other material, or the stopping-out medium may be eaten away or bleached in any convenient manner—for instance, by means of chlorid of lime, zinc, and bisulfite of soda. The decoration 10 may then under some circumstances be complete or the material may be further decorated on only those parts where the stopping-out medium had been or otherwise.

By this invention designs of various kinds 15 may be produced very cheaply and rapidly because neither rollers nor blocks will be required. The necessary endless stencils are produced much more cheaply than are rollers or blocks, and the amount of manual labor is 20 also considerably reduced. Besides this, an unlimited number of effects in design may be obtained and it is possible to leave the groundwork or other parts of the original color or to mask a part of the design previously 25 sprayed in colors.

What we claim as our invention, and desire to secure by Letters Patent, is—

1. A process of stenciling consisting in first applying stopping-out medium through the 30 apertures of a stencil to parts not intended to receive color and then applying color through the apertures of a second stencil, substantially as set forth.

2. A process of stenciling consisting in first

applying stopping-out medium through the 35 apertures of an endless revolving stencil to parts not intended to receive color and then applying color through the apertures of a second endless revolving stencil.

3. A process of stenciling consisting in first 40 spraying stopping-out medium through the apertures of a stencil to parts not intended to receive color and then spraying color through the apertures of a second stencil, substantially as set forth.

4. A process of stenciling consisting in first applying a stopping-out medium, composed of paraffin, beeswax and turpentine, through the 45 apertures of a stencil to parts not intended to receive color, then applying color over and around the said medium through the apertures of a second stencil and finally removing the said medium and the superimposed color by means of a suitable agent, substantially as set forth.

In testimony whereof we have signed our names to this specification in the presence of two subscribing witnesses.
